UNITED STATES PATENT OFFICE.

WALTER B. CULLUM, OF GRAFTON, WEST VIRGINIA.

VALVE.

1,146,850.

Specification of Letters Patent. Patented July 20, 1915.

Application filed April 10, 1914. Serial No. 331,042.

To all whom it may concern:

Be it known that I, WALTER B. CULLUM, a citizen of the United States, residing at Grafton, in the county of Taylor and State 5 of West Virginia, have invented new and useful Improvements in Valves, of which the following is a specification.

The invention relates to an improvement in valves, and particularly to a valve designed for controlling the flow of water in 10 the cooling of plungers in glass bottle production, wherein the flow of the cooling liquid requires to be opened and shut off instantly at predetermined points in the movement of the plunger.

The main object of the present invention is the provision of a valve constructed with a view to an instant closing of the outlet, while at the same time constructing the parts 20 so that they may be readily accessible for renewal or repair.

The invention in the preferred form of details will be described in the following specification, reference being had particularly to the accompanying drawings, in which:—

Figure 1 is an elevation of the valve. Fig. 2 is a vertical central section, partly in elevation, of the same. Figs. 3, 4, and 5 are 30 perspective details.

Referring particularly to the accompanying drawings, the improved valve comprises a casing 1 formed approximately centrally of its length with a restricted passage 2, 35 opening immediately above the same into a valve seat 3, and above the latter into a pressure chamber 4. The restricted passage 2 opens below the same into an operating chamber 5, which latter is practically of 40 uniform bore throughout its length, opening through the end of the casing.

A spherical valve 6 is arranged within the casing to coöperate with the seat 3, and below the valve an operating plunger 7 is provided 45 for the actuation of said valve. The plunger includes a lower portion 8 of uniform diameter, an intermediate portion 9 of slightly less diameter than the diameter of the operating chamber 5 and the upper portion 50 10 adapted to contact with the valve. The upper portion is preferably of angular shape in cross section so as to provide free 55 passages about the same lengthwise the restricted passage 2 to permit the flow of water lengthwise said portion. The operating member is held in position within the casing

by a sleeve 11 exteriorly threaded to coöperate with the appropriate interior threads of the casing, the interior bore of the sleeve being enlarged adjacent its upper end to receive packing 12 secured in place and appropriately compressed by gland 13 threaded into the sleeve. The upper end of the sleeve is designed to be engaged by the disk 9 of the operating member to limit the downward movement of the latter, a spring 14 being coiled about the upper portion of the operating member between the shoulder of the casing at the lower end of the restricted passage 2 and the disk 9. The spring operates to move the member 7 to its lowered or inoperative position, in which position the relatively upper portion 10 of said member is free of contact and below the valve 6, permitting full and free seating of the valve. 75

A support for actuating the lever is provided in the member 15, comprising an annular terminal 16 to fit against the lower end of the casing and a depending arm 17 extending below and in parallel relation 80 to the casing and formed near its lower free end with a slot 18. The lower end of the sleeve 11 is provided with a nut 19 of angular contour to bear against and secure the support in place. The lower or free end of 85 the portion 8 of the operating member is transversely slotted at 20, forming rounded upper walls, the slot receiving an operating lever 21 pivoted at 22 in the slot with one of its ends fitting loosely in the slot 18 of 90 the arm 17. The power end of the lever is formed with an opening 23 permitting the attachment of the lever to any suitable operating means, though it is obvious that it may with equal facility be operated directly 95 by hand. The upper end of the casing forms the inlet, the outlet 24 being formed laterally of the casing immediately below the restricted passage 2, said outlet opening directly from the operating chamber 5. 100 The inlet end of the casing is closed by the coupling nut 25 threaded on to the end of the casing, and formed with a central threaded aperture 26 to receive pipe connection 27, by which fluid is admitted to the 105 valve. The diameter of the opening 26 is less than the diameter of the pressure chamber 4, thereby providing a shoulder at the upper end of said chamber between which and the valve 6 is arranged a spring 28 tensioned to assist in seating the valve. 110

The operating of the improved valve will

be fairly apparent from the above description taken in connection with the drawings, it being understood that while the valve is designed particularly for the use hereinbefore indicated, it is nevertheless readily adapted for the control of other fluids for other purposes, and in all such uses are contemplated as within the spirit of the present invention.

10 What is claimed is:—

A valve including a casing centrally formed with a restricted passage and having a pressure chamber above said passage and an operating chamber below said passage, said valve having an inlet leading to the pressure chamber and an outlet leading from the operating chamber immediately below the restricted passage, a valve seat formed in the casing at the juncture of the pressure chamber and restricted passage, a valve for said seat, pressure means bearing upon the valve to normally seat the same,

a valve operating member movable in the operating chamber and in the restricted passage, said member being of a size to permit 25 the restricted passage to remain open at all times, a sleeve threaded in the casing and forming the lower limit of the operating chamber, a spring arranged in the operating chamber and normally maintaining the 30 operating member in its retracted position, a support having an annular terminal to fit over the sleeve beyond the end of the casing, a nut threaded upon the projecting end of the sleeve to secure the support in place, 35 and a lever loosely mounted in said support and connected with the operating member.

In testimony whereof I affix my signature in presence of two witnesses.

WALTER B. CULLUM.
